United States Patent Office.

OSBORNE MACDANIEL, OF NEW YORK, N. Y.

Letters Patent No. 63,166, dated March 26, 1867.

IMPROVEMENT IN WIRE BALE-TIE.

The Schedule referred to in these Letters Patent and making part of the same.

TO ALL WHOM IT MAY CONCERN:

Be it known that I, OSBORNE MACDANIEL, of the city, county, and State of New York, have invented a new and improved Wire Bale-Tie; and I do hereby declare that the following is a full, clear, and exact description thereof, which will enable others skilled in the art to make and use the same, reference being had to the accompanying drawings, forming part of this specification, in which—

Figure 1 is a front view of my improved bale-tie in one of its forms and modes of connection.

Figure 2 is a modification of form and mode of connection.

Figure 3 is a perspective view of my improved bale-tie represented in another modification of the mode of connection and attached to a bale-hoop.

Figure 4 is a perspective view of the form and mode of connection, shown in fig. 2, and attached to a bale-hoop.

Similar letters of reference indicate corresponding parts.

This invention relates to an improvement in metal ties for securing iron hoops on cotton and other bales and packages; and consists in forming it of wire or small rod iron, by bending the wire into the shape of a stirrup, yoke, or bail, with hooks and eyes, or either of them, on the ends, to be connected and attached to the hoop, as hereinafter described.

My improved wire bale-tie possesses every essential of a perfect fastening for iron hoops on a cotton bale. It is simple in construction, and easily and cheaply manufactured; it combines the greatest strength with the least weight, as wire is the strongest form of wrought iron for bearing tension; it is applied to a hoop by hand instantly when fastened to a bale, without tools, and secures the full strength of the iron hoop, which is not cut or weakened in any manner, and has its ends bent over square and folded flat against the bale, so that both the tie and the ends of the hoop lie close and even on the bale and expose no projections; it cannot slip nor break away under the most powerful strain or concussion that the hoop itself will sustain.

For making my improved bale-tie I prefer annealed wire of suitable size, and, with proper dies and machinery, cut and bend it as desired. It may be somewhat modified in form and mode of connection, by using either double yokes or bails connected, or a single yoke, connected with a tongue or cross-bar by means of hooks and eyes, or either of them.

In fig. 1 the two yokes *a b* are connected with hooks and eyes, and in fig. 2 the yoke *a* and the tongue or cross-bar *d* are also connected by hooks and eyes, to form the tie and fasten it to the ends of a hoop, *A*, as shown in figs. 3 and 4. The yokes *a* and *b*, or the yoke *a* and cross-bar *d*, may be connected or linked together by closed eyes on one of the ends of each, so that the two parts may hang together, while the other side or end of each may be either a hook or a closed eye indifferently, to be connected with each other when the tie is made fast to the hoop on the bale; or the ends may be all left as hooks to be closed upon each other to form eyes or not when the hoop is fastened. It is obvious that any of these several modes of connection may be employed, and that the position of the hooks and eyes may be changed by placing them in the same plane flat against the bale, or at right angles to it, all being modifications simply of the same plan of construction of my wire bale-tie. The method of attaching the tie to fasten the hoop on a bale is manifest.

Having thus described my invention, I claim as new, and desire to secure by Letters Patent—

The construction of a wire bale-tie fastened with hooks and eyes, substantially as herein described.

The above specification of my invention signed by me this 14th day of February, 1867.

O. MACDANIEL.
